APPARATUS FOR SECURING SHEET METAL HEADS TO TUBULAR BODIES

John W. Miller, Toledo, Ohio, and Adolph A. Hale,
Spring Lake, Mich., assignors to Acorn Designing Co., Toledo, Ohio, a corporation of Ohio

Application May 25, 1945, Serial No. 595,774

10 Claims. (Cl. 113—1)

1

This invention relates to mechanism or apparatus for joining metal parts together and more particularly to means for securing heads or end structures in hollow or tubular bodies.

The invention embraces the provision of mechanism, substantially automatic in its operation, for simultaneously securing end structures in a hollow body through distortion of portions of the body wall.

An object of the invention resides in a mechanism of this character embodying means for securing a hollow body as, for example, a muffler shell in fixed position while compound bending dies or instrumentalities are moved into engagement with the end portions of the shell to bend the latter into overlapping engagement with flange portions of end structures or plates assembled in the ends of the shell.

Another object is the provision of electrically controlled hydraulic means for actuating the body clamping means and the instrumentalities for securing end structures in the hollow body.

Another object of the invention is the provision of means brought into action after the end structures are secured in the ends of the hollow body, for discharging the assembly of body and end structures from the machine.

Another object is the provision of means for securing end heads or structures in muffler shells which is of a character readily adjustable and adaptable to accommodate various sizes and shapes of shells.

Still another object of the invention resides in a machine for affixing metallic end plates in a hollow body having inter-connected electric circuit controlling devices for initiating the operation of hydraulic actuators for performing a series of operations upon the body in predetermined sequence and in which such operations automatically occur in proper order upon the actuation of a starting switch by the operator, the arrangement including interlocking controls whereby operations or movements of certain elements must be completed before subsequent or sequential operations of other elements are initiated.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 9 is a detail sectional view taken substantially on the line 9—9 of Figure 3;

Figure 10 is a detail sectional view taken substantially on the line 10—10 of Figure 3;

Figure 11 is a sectional view of the parts shown in Figure 5 illustrating the position of the parts at the completion of the operation of permanently securing an end structure in a hollow body; and

Figure 12 is a schematic view illustrating the electrical and hydraulic circuits forming a part of the invention; and

Figure 13 is a top plan view of the switch actuating means shown in Figure 10.

While there is illustrated an embodiment of the invention as particularly adapted for securing end or head structures in muffler bodies or shells, it is to be understood that the invention may be employed for any purpose wherein the same may be found to have utility.

Referring to the drawings in detail the machine is inclusive of a frame 10 preferably fabricated of case metal of hollow configuration. The frame is formed with a uniplanar surface or bed 11 and an upwardly projecting longitudinally extending tang 12 which extends upwardly into a reciprocally shaped portion 13 formed on the lower portion of each of bed or sub-base plates 14.

In the embodiment of our invention there are two heading units 15 and 16, positioned respectively adjacent each end of the machine and mounted upon the sub-base plates 14, the units being arranged to simultaneously secure end structures in a muffler body. As units 15 and 16 are of substantially identical construction, a description of one will suffice to explain their construction and operation. Interposed between

one side wall of the tang 12 and each of the sub-bases 14 is a jib 13a adjusting screws 17 being carried by the sub-base and cooperating with the jib 13a to regulate the clearance between the tang 12 and the sub-base to attain ease of relative slidable movement of sub-base 14 and eliminate any transverse movement of the sub-base.

Each of the heading units 15 and 16 are arranged for ready longitudinal adjustment along the tang 12. To this end there is mounted upon each end of the frame 10 a bracket 20 in which is journaled a shaft 21, collars 22 and 23 being disposed at each side of the bracket and pinned or otherwise fixedly secured to shaft 21 so that the shaft 21 may be rotated but will remain relatively stationary as far as longitudinal movement is concerned. Each of the units 15 and 16 is inclusive of a housing or casing 18 fixedly secured to a sub-base plate 14 by means of screws 19. Each of the housings 18 of units 15 and 16 is formed with integral spaced wall portions 24 and 25, wall portion 24 being provided with an internally threaded bushing 28 adapted to accommodate the threaded portion 30 of each of the shafts 21, wall portions 25 being provided with guide bushings 29 for each of the shafts 21. The outer extremity of each shaft 21 is formed with a squared or polygonal portion 32 adapted to receive a crank 33 or other suitable tool for rotating shaft and thereby adjusting each unit longitudinally of the frame of the machine. By this means, the machine is rendered adjustable to accommodate mufflers of various lengths. The tang 12 is provided with a centrally disposed longitudinally extending T-shaped slot 34 which is adapted to accommodate locking bolts 35 for securely locking the sub-base 14 of each unit or head to the machine frame. In adjusting the heads 15 and 16, it is necessary to release the nuts 36 carried by bolts 35 so that the heads may be free for longitudinal movement when the shafts 21 are rotated by means of cranks 33.

Means are provided for securely clamping a hollow body or muffler shell in proper position during the end structure securing operation. The muffler clamping means is inclusive of pairs of relatively stationary and movable members 37 and 38. The members 37 are mounted upon the base plates or sub-bases 14 and are secured thereto by means of screws 39. It should be noted that each clamping means and one of the heads or units are carried by a sub-base or plate 14, so that when a unit is adjusted relatively to the machine frame, its adjacent clamping means is also movable therewith. As will be noted from Figure 5 the muffler construction 40 is of a type in which the shell 43 is formed with a pair of spaced peripheral depressions or grooves 41. These grooves not only serve to properly position the end structures 42 in the muffler shell or body 43, but they also provide an effective medium for positioning the muffler assembly in the machine. To this end, the grooves are engaged by beads or projections 45 formed on the clamping members 37 and 38 so as to positively clamp or secure the muffler shell in fixed position against endwise movement during the operation of securing the end structures in the shell. The relatively movable clamping members 38, as shown in Figures 2 and 3, are each fixedly secured to a longitudinally extending shaft 47, carried by each unit 15 and 16. Secured to the rear of each of the housings 18 is a bracket 51 secured thereto by means of screws 52. Each of the brackets 51 is formed with rearwardly extending arms pro-

vided with boss portions 53 and 54 which are bored to receive shaft 47 to journally support the latter.

The movable arm 38 of each clamping means is adjustably secured on the shaft 47 by means of a U-shaped key 49, the leg portions thereof extending into kerfs or grooves formed in the shaft, as shown in Figure 8, the key 49 being secured in engagement with the shaft by means of screws 56. The movable arms 38 are arranged to be operated by hydraulic means. To this end an arm 57 is secured to the outer ends of each of the shafts 47, being held in place by means of a key 58. Each plate or sub-base 14 disposed beneath a heading unit has a rearwardly projecting portion 59 upon which is supported a cylinder 60, the latter being pivotally mounted upon projection 59 by means of a pivot or journal 61. Slidably disposed within the cylinder is a piston 55 which is carried upon the lower end of a pitman or rod 63, the upper end of the cylinder 60 being closed by means of a stuffing gland 64 through which the rod 63 extends. The upper end of rod 63 is threaded into an opening provided in the bight portion of a yoke 66, the latter being pivotally connected by means of a pin 67 to the end of the arm 57. Fluid connections 69 and 70 are made respectively at the lower and upper ends of each cylinder 60 for actuating the piston therein to operate the movable clamping members 38.

As will be seen in Figure 1, the clamping members 38 are spaced apart so as to engage and clamp the ends of a muffler assembly in proper position. While fluid means is employed to actuate the pistons in cylinders 60, there being one cylinder and piston arrangement for each of the arms 38, means are provided whereby the arms 38 will move in simultaneous relation. In the embodiment illustrated, there is fixedly secured to the inner ends of each of the shafts 47 a collar or coupling 73. The collars 73 are provided with squared central openings which slidably receive and accommodate a squared shaft or bridge 75 which is arranged to extend through both collars 73. It should be noted that each of shafts 47 are hollow in order to accommodate the shaft 75. By this means the rotatable movement of clamping arms 38 will always occur simultaneously.

Each of the units 15 and 16 are equipped with instrumentalities for distorting or bending the peripheral end portions 46 of the muffler shell 43 over flange 39 formed on the end structures or muffler heads 42 to secure the end structures permanently in the shell 43. As the instrumentalities for bending the ends of the muffler shell carried by the units 15 and 16 are substantially identical in construction, a description of one mechanism will suffice. Referring particularly to Figures 4 and 5, the housing 18 is adapted to be closed at its outer end by means of a plate 80 which is retained in place by means of screws 81. Secured to the plate 80 by means of screws 83 is a collar or sleeve or fitting 84. Secured to the sleeve 84 is a cylinder 85. Slidably disposed within cylinder 85 is a piston 86 which is secured to the end of a piston rod 87. The piston rod 87 extends through the plate 80 and has a reduced tenon portion 88. Surrounding the tenon portion 88 is a sleeve 89 and a spacing collar 90, as shown in Figure 5. Mounted upon the tenon portion 88 adjacent its juncture with the larger portion of rod 87 is a member 93 which has laterally projecting portions 94 which are bored

to accommodate studs 96, the ends of which are threaded to receive nuts 97 which serve to secure spaced links 98 to the projecting portions 94 of the member 93. Each set of links 98 is pivotally connected to second sets of links 99 by means of studs 100, the latter being adapted to receive nuts 101 to hold the links 98 and 99 in assembled relationship. Disposed between each set of links 99 is a roller or follower 102 which is journaled for rotation upon the studs 100.

The member 93, spacing sleeve 90 and sleeve 89 are fixedly secured to the tenon portion 88 of rod 87 by means of a washer 104 and a headed bolt 105 threaded into an opening in the end of the tenon 88. Surrounding the sleeve 89 are spaced plain bearings or bushings 106 and 107 which are held apart by means of a spacer 109. As shown in Figure 4, the sleeve 89 is provided with a keyway 110 in which is disposed a key 111 for preventing relative rotation of the sleeve 89 but permitting longitudinal movement thereof. Surrounding the sleeve 89 is a second sleeve 113 which is slidably mounted in plain bearings 114 mounted in recesses formed in the wall of the housing 18. The sleeve 113 is also formed with a keyway 116 into which extends a key 117 which is anchored in the side wall of housing 18 and disposed between the bearings 114. Thus through the medium of the keys 111 and 117 the sleeves 89 and 113 are prevented from relative rotation in the housing 18.

As illustrated in Figure 5 there is positioned adjacent each of the rollers or followers 102, a cam or substantially rectangular block 118 which is disposed in a recess formed in the wall of the housing 18. Each of the blocks 118 is mounted for longitudinal slidable movement in the housing and are resiliently held in their normal positions, as shown in Figure 5, by means of expansive coil springs 120 disposed in recesses 121 formed in the plate 80 and held in proper relation with respect to the blocks 118 by means of pilot or guide pins 122. It is to be noted that the ends of blocks 118 abut shoulders 124 formed on the inner walls of the housing 18 and are normally held in this position by means of the springs 120.

The sleeve 113 is formed with rearwardly extending projections 126 which are bored to receive studs 127 which extend through aligned openings in the sets of links 99 whereby the links 99 are pivotally connected to the sleeve 113. The spacer or sleeve 90 is formed with an enlarged cylindrical portion or cam surface 130 which cooperates with the rollers or followers 102 journaled upon the studs 100. As will be hereinafter explained in further detail the cylindrical surface 130 contacts the rollers 102 in order to prevent the sets of links 98 and 99 from attaining a position in which axes of the studs 96, 100, and 127 lie in a single plane. Secured to the sleeve 89 by means of bolts 132 is an instrumentality or member 133 which in the embodiment illustrated as shown in Figure 7 is of cylindrical configuration. It is to be understood that the arrangement as disclosed is to affix end structures in a muffler shell of cylindrical configuration, however it is contemplated that the machine may be utilized for constructions of other shapes by modifying the configuration of the member 133. Surrounding the member 133 is a second instrumentality or member 135 which is of annular configuration when the machine is adapted for a cylindrical muffler. The member 135 has an inner surface arranged to be mounted upon the exterior forward portion of sleeve 113 as shown in Figure 5

and is secured thereto by means of screws 136, the latter having their threaded portions in threaded half round registering openings in the adjacent portions of sleeve 113 and member 135.

- 5 The forward portion of member 135 is provided with a die portion 137 whose inner surface 138 is of the same configuration as the exterior surface of member 133, the latter being arranged for slideable movement relative to the member 137.
- 10 The members 137 and 133 are arranged to be moved successively into engagement with the end flange portion 46 of the hollow body or muffler shell 43 to distort or bend portion 46 into overlapping engagement with flange 39 formed on 15 the end head structure of the muffler assembly as shown in Figure 5. Members 133 are provided with recesses 133' to accommodate the overlap seam on the muffler body. The members 133 and 137 of each heading unit or mechanism are actuated by hydraulic means acting upon the pistons 86, the hydraulic means being electrically controlled by instrumentalities hereinafter described.

The annular member 135 is formed with a laterally extending boss portion 140 to which is secured a plate or bracket 141 which is secured to the annular member 135 by means of screws 142 and 143. Secured to the plate 141 and extending longitudinally of the machine is a U-shaped member or clamp locking means 145 which is held in place by means of screws 146 extending into threaded openings in the bracket 141. As particularly shown in Figure 8, the stationary and movable clamps 37 and 38 are formed with integral forwardly extending projections 148 and 149. These projections are juxtaposed as shown in Figure 8 when the clamps 37 and 38 are in a muffler shell clamping position. As the heads or units 15 and 16 move forward to bring the die members 133 and 137 into engagement with the muffler shell 43, the yoke or locking means 145 is moved forwardly and straddles the projections 148 and 149 serving as a positive clamping means preventing separation of clamps 37 and 38 during the period of time in which work is being performed by members 133 and 137 upon the muffler assembly. Each of the stationary clamps 37 is secured to its adjacent housing 18 by means of struts or rods 71 threaded into openings provided in the housing 18, the rods being locked by means of nuts 74. The rods 71 are secured to the clamps 37 by nuts 76 disposed at either side of the clamp and threaded onto the rods. These rods or struts tie the housing 18 to the clamp 37 and serve to resist the longitudinal stresses imparted to the clamp during the bending operations performed by members 137 and 133.

Means are provided to elevate the muffler assembly 40 out of engagement with the lower clamp 37 after the work operations are performed upon the muffler assembly. This means is inclusive of a pair of arms 150 each arm being secured by means of a key 151 to a shaft 152, the latter being journaled in a bearing carried by web portion 153 forming a part of bracket 151 and in a bearing mounted in the end of an arm 155 which is secured to the stationary clamping element 37 by means of screws 156. Also keyed upon each of the shafts 152 is an arm 157 which is bifurcated at its free end to receive and accommodate a link or bar 154, the latter being adjustably connected to link 158 which is pivoted at one end by means of a pin 156' to a projection 159 formed integrally with the lever or arm 57. The extension or link 154 extends into a furcation formed in

the arm 157, the link extension 154 being provided with a notch 160 arranged to take over a pin 161 carried by the arm 157. The link 154 is connected at its lower end to a contractile spring 162 the other end of the spring being secured to the projecting portion 59 formed upon the sub-base or plate 36. The stress of the spring 162 serves at all times to urge the link 154 into engagement with the pin 161 carried by the arm 157.

Secured to web 153 of bracket 51 is an abutment bar 164 adjustably mounted by means of screws 165 extending through a slot 166 formed in the bar. Mounted in the end of bar 164 is a cylindrical pin 166. Extension 154 is provided with threaded openings to receive screws 168 which extend through a slot 169 in link 158 to secure the extension 154 to the link 158. Adjustment may be made between the link 158 and the extension link 154 by means of the screw and slot arrangement. Carried by the link 158 is a block or member 170 which is arranged to engage pin 166 upon clockwise movement of pin 158' about the axis of shaft 47 when the clamps 38 are swung to a position out-of-use. The engagement of block 170 and pin 166 causes relative hinging movement of link 153 and extension 154 to disengage the notch 160 from pin 161, which action permits the arm 157 to swing in a counter clockwise direction as viewed in Figure 2 about the axis of shaft 152 and thus the arms 150 swing downwardly by gravity, the lowermost position of the arms being determined by adjustable stops or abutments 144.

The abutments 144, as shown in Figure 8, are each provided with a slot 147 through which extend screws 171 threaded into the arm or projection 155. The abutments 144 may be adjusted to determine the position of arms 150 for accommodating muffler assemblies of different sizes.

The coordinated actions and movements of the several instrumentalities or elements in their proper sequential relationship are initiated and controlled by electrical means in cooperation with hydraulic means to permanently secure the end structures in the muffler shells or the like. An electrical switch means 180 is arranged to control or permit movement of the clamping arms 38. Mounted upon one of the shafts 47 is a collar 182 which is pinned or otherwise fixedly carried upon the shaft. As shown in Figures 3 and 9, the collar 182 supports a cam or disc 183 the latter being provided with a pair of diametrically opposed arcuate slots 185 which are adapted to receive and accommodate screws 186 which are threaded into openings formed in the collar 182. By this means the disc 183 may be adjusted so that the recessed surface 187 and the ramps 188 and 189 may cooperate properly with a roller 190 journaled upon the outer end of a switch arm 191, the latter being pivoted upon a pintle 192 associated with switching mechanism or circuit controlling means contained within a switch box or housing 193. The switch box 190 is supported upon a bracket 181 carried by the member or bracket 51.

Each of the heading units 15 and 16 is provided with a switch mechanism forming an auxiliary means determining the completion of movement of the instrumentalities in the performance of the flanging operation upon the muffler shell. As will be hereinafter explained the several switch mechanisms are intercalated in electrical circuits in order to control the application of an hydraulic medium to operate the various

instrumentalities. As shown in Figures 4, 6 and 10, the housing 18 is formed with an opening 200 which is normally closed by means of a plate 201 held in position by means of screws 202. Welded to plate 201 and depending therefrom is a cylindrical projection 203 which is bored to accommodate a bearing or bushing 204. Journaled within the bearing 204 is a shaft 207, the lower end of the shaft being bifurcated to receive a laterally extending finger 208 secured to the shaft by means of rivets 209. The shaft extends upwardly and immediately above the plate 201 is surrounded by a disc 210. Superposed above disc 210 is a member 211 having a cylindrical recess larger than the diameter of shaft 207 within which is disposed a coil spring 213, the lower end portion of the spring extending radially and lying in a radial groove 214 formed in the upper surface of disc 210, the other end of the spring extending into an opening formed in the shaft 207. The member 211 is formed at its lower end with a flange 216 having a sector shaped recess 217 within which projects the upper end of a pin 218 fixedly mounted in disc 210 and plate 201. The member 211 is adapted to rotate with the shaft 207, being secured thereto by means of a bolt 206. The upper end of shaft 207 is formed with a substantially rectangular portion to receive the bifurcated extremity of a laterally extending arm 220, the latter being secured to shaft 207 by means of a bolt 221. An opening in the arm 220 is threaded to receive an abutment screw 222 which may be adjusted relative to the arm 220 and locked in proper position by means of a nut 223. The abutment screw 222 is adapted to engage a roller 224 journaled at the end of a switch arm 226, the latter associated with switching mechanism contained within the housing 228, the latter being supported upon the housing 18. The member 93 carried upon the shaft 88 is provided at its upper portion with a threaded opening to receive a threaded tenon 229 integrally formed on a member 230. The member 230 is so disposed that as the die member 133 approaches its forward limit of movement, the member 230 will engage the laterally extending finger 208 and rotate shaft 207 and arm 220, causing the abutment screw to engage roller 224 on switch arm 226 to initiate the operation of the switch for a purpose to be hereinafter explained. The coil spring 213 is arranged to cooperate with shaft 207 and the member 211 to return the shaft and mechanism carried thereby to their normal position when the arm 208 is out of engagement with member 230. The walls bounding the extremities of the recess 217 in flange 216 of member 211 cooperate with pin 218 to define the limits of rotary movement of shaft 207.

Figure 12 illustrates the electrical circuits, switches and other instrumentalities forming the actuating and control system for the hydraulic means utilized for actuating the pistons 86 in cylinders 85 and pistons 55 in cylinders 60. In Figure 12 the designations L1 and L2 indicate the respective current supply lines of a two wire system. A starting switch 240 is connected to a magnetic contactor switch 242, the latter having dual sets of contacts 243 and 244. The contact 243 is connected to a solenoid contained within housing 246 for initiating the movement or operation of hydraulic valve control means contained within housing 247. The contact 244 is connected through an emergency stop switch 253 to contact 249 of a switch 250 and with contacts

251 of a similar switch 252. The contact 254 of switch 253 and contact 255 of switch 252 are connected together. Another magnetic contacter switch 260 of the same character as switch 242 is provided with contacts 261 and 262, contact 261 being connected to contact 258 of switch 250 and to the emergency stop switch 253. Contact 275 is connected to the switch mechanism 180 and contact 261 is connected to a solenoid contained within housing 265 for controlling the operation of hydraulic valve mechanism contained in housing 247.

The hydraulic circuits are also shown in Figure 12 together with other instrumentalities and valve arrangements for directing the flow of fluid under pressure to the various cylinders or hydraulic actuators in the proper sequence of operation. It is to be noted that the machine frame 10 is of a hollow configuration and provides ample space to accommodate a fluid reservoir and motor-driven fluid pump and other accessories forming part of the hydraulic actuating system. As indicated in the schematic diagram of Figure 12, the fluid reservoir 270 provides a support for an electric motor 271 which is adapted to drive a dual type hydraulic pump contained within a housing 273. The pump housing is provided with an oil inlet 274 extending into the reservoir 270. The oil pump is of a conventional high and low pressure stage construction. It has been found that for high pressure use, a pressure of approximately 850 lbs. per square inch is satisfactory the pressure being controlled by a pressure relief valve 276. The low pressure side of the pump is controlled by means of a relief valve 278 so as to establish in certain of the fluid lines a pressure of approximately 80 lbs. per square inch. The low pressure fluid lines in the diagram of Figure 12 are illustrated by heavy broken lines, the fluid pressure in these lines being utilized to actuate the hydraulic control valves contained within housing 247, the position of these valves and their operation being controlled by the solenoids 246 and 265 for purposes hereinafter explained. The reservoir 270, motor 271, and pump 273 and associated accessories may be housed within the hollow interior of the machine frame or in any other convenient location. Further explanation of the various instrumentalities and circuits, both electrical and hydraulic, will be given in connection with the operation of the machine of the present invention.

A full cycle of operations of the machine and its various elements in securing heads or end structures in a muffler assembly is as follows: The operator first places a muffler shell assembly 48 or the like in the lower clamps or supports 37. The end structures 42 have been pre-assembled within the muffler shell or body 43 and are positioned in the shell by means of their engagement with the inwardly extending circumferential ridge 45' as shown in Figure 5. The clamps 37 are provided with beads or ridges 45 which extend into the grooves in the muffler shell formed by the ridges 45'. Thus the engagement of the beading 45 in the grooves provides a positive means for properly positioning the muffler assembly in the stationary supports or clamps 37. It is to be understood that the levers or arms 150 are at their lowermost position so as to be out of engagement with the muffler assembly, during the work performing operations. After the pre-assembled muffler is in the position above mentioned, the machine operator manually depresses the starting button of starting switch 240 to com-

plete an electrical circuit from a power source of electrical energy to the magnetic contacter switch 242. As soon as the starting switch 240 completes the circuit therethrough to the coil 241, which then energized closes respectively contacts 244 and 243, the closing of contacts 243 completes the electric circuit through wire 245 to the solenoid 246 which actuates the latter to initiate an hydraulic control means associated therewith so that the low pressure fluid circuit in hydraulic line 256 to actuate a main hydraulic control valve (not shown) disposed in housing 247. This movement of the main valve causes fluid in the high pressure hydraulic line 257 to pass through the valve housing 247 into the hydraulic line 258 to a sequence valve 259. The sequence valve 259 is so arranged that oil or fluid from line 258 will flow through the sequence valve, through line 300, and through the Siamese lines 301 and 302 to the upper ends of the cylinders 60 through the inlet pipes 70. The fluid, being under comparatively high pressure, moves the pistons 55 downwardly thus swinging the movable clamping arms 38 downwardly in a counterclockwise direction as viewed in Figure 2, causing the semi-cylindrical recessed portion of each arm to engage the upper end portions of the muffler shell 43 so that the upper and lower clamps 38 and 37 conjointly and securely retain or anchor the muffler assembly in proper position. The upper clamp 38 is provided with a tenon 68 which registers with and extends into a recess in the lower clamp 37 so that the clamping members are maintained in proper relation when in muffler clamping position.

When the pistons 55 have moved downwardly a sufficient distance to bring the clamps 38 into clamping position, viz. in engagement with clamps 37, further downward movement of the pistons 55 is thus prevented with a consequent rapid rise in the fluid pressure in the lines 301 and 302. When this pressure reaches a predetermined value depending upon the pressure setting of the sequence valve 259, the latter is provided with a movable element or valve (not shown), which is actuated by reason of the increase in fluid pressure in the sequence valve, to divert the fluid flow to the outlet 305, thence to the Siamese lines 306 and 307 which lead respectively to the outer ends of the cylinder 85.

The advent of fluid under pressure to the cylinders 85 reacts against the pistons 55 to simultaneously move each of the rods inwardly, or as viewed in Figure 5, in a left-hand direction. As the rod 87 progresses inwardly it carries with it the member 93. By reason of the engagement of rollers 102 with the inner surfaces of blocks or cams 118, the links 93 and 99 together form a toggle arrangement through which the sleeve 89 is moved to the left carrying with it the member 133 and the member 135. It should be noted that the chamfered entrance 139 of the forming ring or die 138 is brought into engagement with the end portion 46 of the muffler shell 43. The angular or chamfered surface 139 distorts or bends the end portion 46 inwardly at an angle substantially that of the angularity of the surface 139. At the completion of this distortion or bending of end portion 46 by the ring 138, the rollers 102 have progressed or traveled to a point where they are permitted to move outwardly along the cam or inclined surfaces 125 formed at the ends of the blocks 118. As the rollers 102 move outwardly further forward movement of sleeve 89 and ring 138 does not take place

as further left-hand movement of rod 87 results in the lateral collapsing of the links 98 and 99, as shown in Figure 11. The rod 87, however, continues its left-hand movement, as viewed in Figure 5, bringing the angularly disposed entrance wall 134 of the plunger die or member 133 into engagement with the end portion 46 of the muffler shell which has previously been bent at an angle by its engagement with surface 139 of member 133. Further movement in a left-hand direction of member 133 completely bends or distorts the end portions 46 of the muffler shell upon itself and in overlapping relationship with the flanges 39 formed on the muffler end structure. It is to be understood that the sequence of operations of members 137 and 133 are taking place substantially simultaneously in each of the units or heads 15 and 16, so that the end structures in each end are simultaneously fixedly secured by distortion of the end portions 46 of the shell. Thus, longitudinal pressures acting to dislodge the muffler shell from the clamps 37 and 38 are substantially equalized or balanced out in view of the fact that the hydraulic pressures in hydraulic lines 306 and 307 are substantially equal.

Should one heading unit encounter increased resistance in securing an end structure in the muffler as compared with that encountered at the other end then a differential of pressure acting longitudinally of the muffler shell may momentarily arise. However, the yokes 145 have previously straddled the projections 148 and 149 formed on the clamps 37 and 38, this occurring during preliminary movement of member 137, so that unbalanced longitudinal pressures will not dislodge the muffler assembly as the clamps are securely locked together by the yokes 145.

As each of the units 15 and 16 is provided with a switching means viz. unit 15 supporting the switch 250 and unit 16 supporting the switch 252, they are interconnected so that both pistons 86 must be moved to their innermost positions, completely flanging each end portion 46 of the muffler shell over its adjacent end closure before the fluid pressure is released in the lines 306 and 307. In order to assure that each end closure is properly fastened by means of the overlapping of portion 46, the contact 255 of switch 252 and 254 of switch 250 are connected by a common connector 309. Thus the movable switch arms 226 must both be actuated by engagement with members 230 to close contacts 254 and 258 in switch 250, and contacts 255 and 259 in switch 252, before a circuit is completed from the power line or current source through connector 309 and connector 310 to actuate the coil 272 in magnetic contacter switch 260 to complete the circuit from the current supply through contact 262 and connector 311 to energize solenoid 265, the latter controlling fluid flow from the low pressure line 312 to actuate valve means contained within housing 247 to divert fluid from the main high pressure fluid line 257 through outlet 314 to sequence valve 315, the fluid passing through Siamese lines 316 and 317. Thus fluid under pressure is directed against the opposite sides of pistons 86 in cylinders 85 so as to cause the pistons 86 and forming dies 133 and 137 to be retracted from the muffler assembly, such movement continuing until the pistons 86 reach their extreme outermost positions. When the pistons reach this position pressure rises in fluid lines 316 and 317 and in the sequence valve 315, causing fluid from the inlet 314 to be diverted to the

Siamese lines 318 and 319 to direct fluid under pressure to the lower ends of the cylinders 60 through the tubes 69 and beneath the pistons 55. Under the influence of fluid pressure, pistons 55 are moved upwardly and as viewed in Figure 2, causes the movable clamps 38 to be moved upwardly in a clockwise direction away from the muffler assembly 40 supported in the lower clamps 37. As the arms 38 move away from the muffler assembly, the pin 161 engaging in notch 160 formed in member 154, the members 158 and 162 are caused to move downwardly. As pin 161 is mounted in the arm 157, the latter will be rotated about the axis of shaft 152 causing the forwardly extending arms 150 to swing upwardly into engagement with the exterior surface of the muffler assembly to elevate the latter above the supports or stationary clamps 37. The arms 150 and the muffler assembly move upward until the arms reach an angular position sufficient to cause the muffler assembly to roll along the arms 150 and rearwardly of the machine to discharge the latter on to a conveyer or other suitable receiving means. When the arms 150 have reached an angular position wherein the muffler carried thereby is discharged, the abutment 170 carried by member 153 engages the stop member 166 carried by member 164, causing members 158 and 154 to swing in a counterclockwise direction as viewed in Figure 2 about the shaft 158' thus moving member 154 rearwardly and disengaging the notch 160 from pin 161. When this occurs, the arms 150 swing downwardly in a counterclockwise direction about shaft 152 and out of the way so that another muffler shell and unsecured end structure assembly may be placed in the supporting clamps 37, and the cycle of operations above described may be repeated.

As the clamps 38 approach their uppermost limits the switch 180 is actuated by the cam disc 183 so as to break the circuit through switch 180. As switch 180 is connected to one of the contacts in switch 260 by means of a connector 320, the breaking of the circuit through switch 180 de-energizes the coil 272 in the contactor switch 260 and, through the switch 260 breaks the circuit involving connector 311 and solenoid 265, to cause the latter to move the main valve in the valve housing 247 out of registration with the outlet 314 and to a neutral position wherein there is no fluid under pressure passing from the valve housing 247 into any of the hydraulic lines. Thus, as switch 180 is the last instrumentality acted upon in the cycle of operations above described, it operates to restore the status quo in the electrical circuits and in the hydraulic circuits in preparation for a repetition of the series of operations upon the next muffler assembly. As the breaking of the circuit by switch 180 de-energizes magnetic contactor switch 260, and as switches 250 and 252 have been broken by retractive movement under the influence of springs 213 by reason of the pins or members 230 moving away from the arms 208, there is no current flowing through any of the electric circuits. In the event that an irregularity is encountered, as for example, an imperfect muffler body being inserted, the blocks 118 under the excessive pressure of rollers 102 will compress springs 120 and thus prevent further forward movement of die member 137. Furthermore, the cycle of operations may be interrupted at any stage by simply depressing the emergency stop switch 253.

After the operator has placed a new muffler

shell and end structure assembly in the machine, it is only necessary for the operator to again depress the starting button on starting switch 240 in order that the sequence of operations above described will be carried out with each successive muffler assembly placed in the machine.

It is apparent that, within the scope of the invention, modifications and different arrangements may be made other than is herein disclosed, and the present disclosure is illustrative merely, the invention comprehending all variations thereof.

What we claim is:

1. Apparatus for performing operations on the ends of a hollow body including a frame; a pair of housings supported upon said frame; means associated with each of said housings adapted to support a hollow body between said housings and upon which work is to be performed; a pair of metal forming dies telescopically arranged and reciprocably supported in each of said housings; hydraulically actuated means for moving said metal forming dies into engagement with the end portions of the hollow body; means associated with one of the dies in each housing whereby movement thereof is arrested after the same has reached a predetermined position; each of said die arresting means including a relatively movable control member; a spring supporting each of said members and adapted to be compressed when said die encounters excessive resistance in engaging the hollow body; and means to reverse the direction of movement of the hydraulically actuated means and the pairs of metal forming dies after completion of the work.

2. In combination, a frame; a pair of housings adjustably supported upon said frame; means associated with each of said housings adapted to support a muffler assembly upon which work is to be performed; a clamping arm pivotally supported adjacent each of said housings and adapted to be moved into clamping engagement with the muffler assembly adjacent the supporting means; a pair of metal forming dies telescopically arranged and reciprocably mounted in each of said housings; means to move said dies into engagement with the muffler assembly to perform work thereon; means including a cam block and cooperating roller for stopping forward movement of one of said dies of each set after the same has reached a predetermined position in engagement with the muffler assembly; means to reverse the direction of movement of the die moving means and dies upon completion of the work; means automatically brought into operation after completion of the work performing operations to move said clamping arms away from the muffler assembly.

3. In combination, a frame; a pair of housings adjustably supported upon said frame; means associated with each of said housings adapted to support a muffler assembly upon which work is to be performed; a clamping arm pivotally supported adjacent each of said housings and adapted to be moved into clamping engagement with the muffler assembly adjacent the supporting means; a pair of metal forming dies telescopically arranged and reciprocably mounted in each of said housings; means to move said dies into engagement with the muffler assembly to perform work thereon; means including a cam block and cooperating roller for stopping forward movement of one of said dies of each set after the same has reached a predetermined position in engage-

ment with the muffler assembly; electrically controlled means to reverse the direction of movement of the die moving means and dies after completion of the work performing operations; means automatically brought into operation after completion of the work performing operations to move said clamping arms away from the muffler assembly, and means set into operation by movement of said clamping arms away from the muffler assembly for elevating the latter from the supporting means and discharging same therefrom.

4. In combination, a frame; a pair of housings adjustably supported upon said frame; means associated with each of said housings adapted to support a muffler assembly upon which work is to be performed; a clamping arm pivotally supported adjacent each of said housings and adapted to be moved into clamping engagement with the muffler assembly adjacent the supporting means; a pair of metal forming tools telescopically arranged and reciprocably mounted in each of said housings; means to move said tools into engagement with the muffler assembly to perform work thereon; a yoke carried by a tool of each set and movable with said tool into locking engagement with a muffler assembly supporting means and the adjacent clamping arm; means including a cam block and cooperating roller for stopping forward movement of one of said tools of each set after the same has reached a predetermined position in engagement with the muffler assembly; means to reverse the direction of movement of the tool moving means and tools after completion of the work performing operations; means automatically brought into operation after completion of the work performing operations to move said clamping arms away from the muffler assembly, and means set into operation by movement of said clamping arms away from the muffler assembly for elevating the latter from the supporting means and discharging same therefrom.

5. In combination, a frame; a pair of housings adjustably supported upon said frame; means associated with each of said housings adapted to support a muffler assembly upon which work is to be performed; a clamping arm pivotally supported adjacent each of said housings and adapted to be moved into clamping engagement with the muffler assembly adjacent the supporting means; a pair of metal forming dies telescopically arranged and reciprocably mounted in each of said housings; means to move said dies into engagement with the muffler assembly to perform work thereon; a yoke carried by a die of each set and movable with said die into locking engagement with a muffler assembly supporting means and the adjacent clamping arm; means including a cam block and cooperating roller for stopping forward movement of one of said dies of each set after the same has reached a predetermined position in engagement with the muffler assembly; a spring supporting said cam block; said block being adapted to recede when the tool encounters excessive resistance in engaging the muffler assembly; electrically controlled means to reverse the direction of movement of the die moving means and dies after completion of the work performing operations; means automatically brought into operation after completion of the work performing operations to move said clamping arms away from the muffler assembly, and means set into operation by movement of said clamping arms away from the muffler assembly for ele-

vating the latter from the supporting means and discharging same therefrom.

6. Apparatus for performing operations upon the ends of tubular members comprising in combination, a frame; a pair of spaced housings carried by the frame; means for supporting a tubular member between the housings; a rod reciprocably supported in each of said housings; hydraulic means for actuating said rods; a metal forming die associated with each rod and movable therewith; a second metal forming die telescopingly arranged for reciprocatory movement adjacent each of said first mentioned dies; means including a plurality of links connecting each of said second mentioned dies to the rod adjacent thereto; said second mentioned dies being arranged to be actuated by said rods; means controlling the direction of movement of said links whereby movement of said second mentioned dies is arrested when said dies are moved to a predetermined position while said first mentioned dies are subjected to continued movement by said rods, and means associated with each of said housings arranged to be engaged by said rods for actuating said hydraulic means to return said rods and said dies to their initial positions.

7. Apparatus for simultaneously performing bending operations on the ends of hollow bodies including in combination a frame; a pair of spaced housings adjustably carried by the frame; means for supporting a hollow body between the housings; a rod reciprocably supported in each of said housings; a metal forming die associated with each rod and movable therewith; a second metal forming die telescopingly arranged adjacent each of said first mentioned dies; means including pairs of interconnected links connecting each of said second mentioned dies to the rod adjacent thereto; electrically controlled, hydraulically actuated means for moving said rods and dies; means controlling the path of the pairs of links whereby movement of said second mentioned dies is arrested as said dies reach a predetermined position while said first mentioned dies are subjected to continued movement by said rods, and electrically interconnected means arranged to be engaged by said rods for actuating said hydraulic means to effect return movement of the rods and dies.

8. In combination, a frame; a housing supported upon the frame; means associated with the housing adapted to support a hollow body upon which work is to be performed; a pair of metal forming dies telescopingly arranged and reciprocably supported in said housing; means for actuating said pair of metal dies into engagement with the end portion of the hollow body; means associated with one of said forming dies whereby forward movement thereof is arrested after it has been moved to a predetermined position while said first mentioned dies are subjected to continued movement by said rods; said die arresting means including a movably mounted control member; resilient means engaging the control member for maintaining the latter in a predetermined relative position; said control member being movable to compress the resilient means when one of the dies encounters excessive resistance in engaging the hollow body.

9. Apparatus for performing operations on the ends of a hollow body including, in combination, a frame; a pair of housings adjustably supported

upon said frame; means associated with each of said housings adapted to support a hollow body between said housings; a pair of metal forming dies mounted for telescopic movement one within the other supported in each housing; electrically-controlled hydraulically-actuated means for moving said pairs of metal forming dies into engagement with the end portions of the hollow body; means including a plurality of links connecting one of the dies of each pair to the hydraulically-actuated means; means associated with said pairs of links whereby movement of the die connected thereto is arrested after it has reached a predetermined position without interrupting the movement of the other of said pairs of dies; said die arresting means including a resiliently supported control member for controlling the direction of movement of said pairs of links; and electrically-controlled means to reverse the direction of movement of the hydraulically-actuated means and the metal forming dies after completion of operations upon the ends of the hollow body.

10. Apparatus of the character disclosed, in combination, a supporting means for a hollow body having end heads disposed therein; means including clamps movable into engagement with the hollow body for securing the latter in the supporting means; means for actuating said body securing clamps; means for forming an end of the hollow body including a pair of metal forming dies telescopingly arranged for relative reciprocal movement; actuating means including a rod for moving said metal forming dies simultaneously for a predetermined period of travel; means associated with one of said die elements for interrupting the movement thereof; controlling means for said die actuating means; means associated with said rod and engageable with said controlling means to render the die actuating means effective to retract said die elements after completion of the forming operations on the hollow body; means for initiating operation of said clamp actuating means to release the clamp upon completion of the forming operations; means for removing the hollow body from the supporting means, and means set into operation upon retractive movement of said dies to actuate said body removing means.
